UNITED STATES PATENT OFFICE.

LESTER DOAK, OF McMINNVILLE, TENNESSEE.

FOUNTAIN MOP.

Application filed March 17, 1926. Serial No. 95,402.

The invention has for its object the provision of a fountain mop for oiling floors and other desired surfaces and for cleaning walls, plate glass and analogous surfaces requiring the application of water thereto jointly with a mop.

The invention provides an article of the nature aforesaid which may be readily assembled, dismembered, or adjusted, as desired and which admits of the liquid being fed from the fount to meet requirements.

While the drawings illustrate a preferred embodiment of the invention it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is an elevational view of a fountain mop embodying the invention, parts being broken away.

Figure 2 is an enlarged detail sectional view of the mop, fount, and associated parts,

Figure 3 is a detail view showing parts detached and relatively disposed in a group,

Figure 4 is a view similar to Figure 2, of a modification, and

Figure 5 is a plan sectional view on the line 5—5 of Figure 4.

Corresponding and like parts are referred to in the following description and designated in the several views of the drawings by like reference characters.

The mop comprises a handle 1 and a head fitted to the handle, comprising a fount 2 and a bunch of thrums 3 constituting tufts of suitable material, or a cloth or like member. The end of the handle 1 is preferably tapered and is adapted to be forced into the central opening of the fount 2.

In the preferable construction the fount 2 is of annular formation and comprises an inner wall 3^a and an outer wall 4, the space between such walls being closed at the top and bottom in any preferred way, as by curving edge portions of the outer wall 4 inwardly to meet the inner wall 3^a to which they are attached in any determinate way. Flanges or collars 5 and 6 project from the

top and the bottom of the fount 2 and may consist of extensions of the inner wall 3^a. The collars or extensions 5 and 6 are adapted to receive fastenings 7 when employed to secure the mop head to the handle 1. The bottom flange or collar 6 is outwardly flared, as shown most clearly in Figures 2 and 4 to admit of thrums or tufts being secured thereto by means of a suitable binder 8. Spaced annular beads 9 project outwardly from the outer wall of the fount 2 and in conjunction with a binder 10 secure the thrums, tufts, or like member 3 in place.

In the construction shown in Figure 2, a tube 11 extends through the fount 2 and projects through the top thereof and through the lower portion of the inner wall 3^a and has an outlet in its lower end which is normally closed by means of a valve 12, the stem of the valve extending through the tube 11 and through a cap 13 threaded to the upper end of the tube and closing the same. The upper projecting end of the valve stem terminates in a button 14 which is adapted to be gripped when opening the valve 12 by exerting a pull upon the projecting end of its stem. A coil spring 15 within the tube 11 and around the stem of the valve 12 normally exerts a pressure to hold the valve seated. An opening 16 in a side of the tube 11 adjacent the lower end of the fount provides a discharge for the liquid contents of the fount when the valve 12 is moved to uncover the opening 16 and the outlet in the lower end of the tube 11. The valve 12 closes both the lateral opening 16 and the discharge outlet in the end of the tube. It is observed that the valve 12 may be moved to uncover the opening 16 more or less to regulate the rapidity of the discharge of the contents of the fount. It is also noted that the stem of the valve 12 has a loose fit in the cap 13 to admit air into the tube 11 to replace the water drawn from the fount when the valve 12 is unseated. The air enters the fount through the opening 16, and passes around the valve 12 which fits loosely within the tube 11.

When assembling the parts the thrums or tufts, or the like, are passed through the central opening of the fount so as to project beyond the top and the bottom thereof. Other thrums or tufts 3 are arranged exterior to the fount and the thrums or tufts passing through the central opening thereof and are secured to the outwardly flared or

curved flange or collar 6 by means of a suitable binder 8, after which the upper portion of the thrums or tufts secured by the binder 8 are folded thereover and the ends of the 5 thrums or tufts projecting above the fount 2 are folded thereover and secured by means of the binder 10. The tapered end of the handle 1 is now pressed into the central opening of the fount 2 and secures the 10 thrums or tufts therein by means of a wedging action which also serves to secure the handle to the head. If preferred, other fastenings 7 consisting of sprigs may be driven through the collars or flanges 5 and 6 into 15 the handle 1, as shown most clearly in Figures 4 and 2.

The binder 8 may consist of cord or analogous means and the binder 10 preferably consists of a metal strap having an eye 17 20 at one end through which the opposite end of the strap is passed and bent upon itself after the binder has been closely drawn about the thrums or filaments 3, comprising the mop head.

25 In the construction shown in Figure 4, the annular ribs 9 consist of folds or crimps formed in the outer wall 4. The inwardly deflected edge portions of the outer wall 4 may be soldered or otherwise secured to the 30 edge portions of the inner wall 3^a. A filling opening is provided in the top of the fount 2 and a collar 18 projects from the fount in line with the filling opening and receives a cap 19. A plurality of small openings 20 are formed in the lower portion of the inner wall 3^a adjacent the bottom of the fount for the discharge of the contents of the fount to supply the mop when in active service. When the cap 19 is removed the fount may 40 be filled, the filling opening being closed by replacing the cap 19 upon the collar 18. When the mop is arranged with the discharge openings 20 in lowered position the contents of the fount passes from the latter through the openings 20 and supplies the mop, as will be readily understood. When the fount contains a quantity of liquid and it is desired to prevent waste thereof, the mop is inverted so that the openings 45 50 20 are in upper position, thereby preventing the liquid contents in the lower portion of the fount from discharging through the elevated openings 20. When found necessary the flow of the liquid from the fount through the openings 20 may be regulated by loosening the cap 19 more or less as will be readily appreciated.

55 In the arrangement shown in Figure 2, the fount is supplied by removing the cap 13 from the tube 11 and withdrawing the valve from the tube, the latter receiving the

liquid which passes into the fount through the lateral opening 16.

Having thus described the invention, I claim:

65 1. A mop comprising an annular fount provided with an outlet in its inner wall, thrums passing through the opening of the fount and extending across the outlet in the inner wall thereof and a handle set into the opening of the fount and serving to secure the thrums therein.

70 2. A mop comprising an annular fount having a longitudinal flange in line with the opening therethrough, thrums secured within the opening of the fount and enclosing the latter, and other thrums secured to the said flange beyond the fount.

75 3. A mop comprising an annular fount having an outwardly flared flange in line with the inner wall, thrums passing through the opening of the fount and folded about the inner and the outer walls thereof, means for securing the outer ends of the thrums to the outer wall of the fount, a handle for 80 securing the inner ends of the thrums to the inner wall of the fount and other thrums disposed between the folded end portions of the first mentioned thrums and secured to the said flange beyond the fount.

85 4. In a mop, an annular fount, thrums secured within the opening of the fount, a tube extending through the fount and having a discharge opening at its lower end, and a lateral opening in communication with the fount, a valve within the tube for controlling the discharge opening thereof and having its 90 stem projecting beyond the top of the fount and a spring within the tube normally exerting a pressure to hold the valve closed.

95 5. A mop comprising an annular fount provided with upper and lower collars in line with the central opening of the fount, the lower collar being outwardly flared, said fount having spaced ribs upon its outer wall, a filling opening in its top and a discharge opening in the lower portion of the inner wall adjacent the bottom, thrums passing through the opening of the fount and folded to embrace the inner and the outer walls thereof, a binder securing the outer ends of the thrums to the outer wall of the fount opposite the space between the said ribs, a handle inserted in the opening of the fount and confining the inner ends of the thrums therein, other thrums disposed about the lower collar between the folded ends of the first mentioned thrums and a binder securing the last-mentioned thrums to the said 100 lower collar.

110 In testimony whereof I affix my signature.
LESTER DOAK. [L. s.]
